Primary Examiner — Kimberly Barnes*(74) Attorney, Agent, or Firm* — R. William Graham**CLAIM**

The ornamental design for a self erecting protective shielding device, as shown and described.

DESCRIPTION

FIG. 1 is a perspective view of a self erecting protective shielding device showing my new design;

FIG. 2 is a top view of a self erecting protective shielding device showing my new design;

FIG. 3 is a bottom view of a self erecting protective shielding device showing my new design;

FIG. 4 is a front side elevation view of a self erecting protective shielding device showing my new design;

FIG. 5 is a back side elevation view of a self erecting protective shielding device showing my new design;

FIG. 6 is a right side elevation view of a self erecting protective shielding device showing my new design; and,

FIG. 7 is a left side elevation view of a self erecting protective shielding device showing my new design.
